FIG. 1 is a top, front perspective view of an alarm clock with media player dock showing my new design;
FIG. 2 is a side view thereof, the opposite side view being a mirror image;

FIG. 3 is a bottom view thereof;

FIG. 4 is a rear view thereof;

FIG. 5 is a front view thereof;

FIG. 6 is a top view thereof; and,

FIG. 7 is a cross-sectional view along line 7—7 in FIG. 5.

The broken line in the drawings illustrate environmental material that forms no part of the claimed design. The claim is as shown and described.
